CLAIM

The ornamental design for a bottle cap, as shown and described.

DESCRIPTION

FIG. 1 is a front perspective view of a bottle cap showing our new design in a closed position;

FIG. 2 is a front elevation view thereof;

FIG. 3 is a rear elevation view thereof;

FIG. 4 is a right side elevation view thereof;

FIG. 5 is a left side elevation view thereof;

FIG. 6 is the top plan view thereof;

FIG. 7 is the bottom plan view thereof;

FIG. 8 is a front perspective view thereof showing the bottle cap attached to a bottle; and,

FIG. 9 is a front perspective view of the bottle cap shown in FIG. 1, in an open position.

The broken lines are shown for the purpose of illustrating both parts of the article as well as environmental subject matter of an exemplary bottle. None of the broken lines form part of the claimed design.
